MACHINE FOR OPERATING ON SHOES

Norwood H. Knowlton, Rockport, Mass., assignor
to United Shoe Machinery Corporation, Borough of Flemington, N. J., a corporation of New Jersey

Application May 26, 1939, Serial No. 275,944

7 Claims. (Cl. 12—51)

This invention relates to machines for operating on shoes, and is herein illustrated as embodied in a machine for pounding and ironing the bottom of a shoe after it is lasted and before the outer sole is attached.

In the manufacture of many kinds of shoes, particularly of the McKay type, it is necessary, after the upper has been lasted in over the insole, to treat the lasting margin so that the bottom of the shoe will present a smooth, flat surface to which the outsole may be attached. To this end, it is usual to employ a bottom pounding machine, one common type of which comprises a rotating cylinder with a series of axially arranged spindles each carrying a row of loosely mounted pounding rings, which, under the influence of centrifugal force, beat against the bottom of the shoe.

To supplement the pounding machine, however, it is desirable to employ some means for ironing out the lasting margin in order to remove any wrinkles or ridges that may be left by the pounding rings, and to level out any high spots that may remain because of the tendency of the rows of pounding rings to conform to the curvature of the shoe bottom. Such an operation must at present, however, if it is performed at all, be carried out as a separate step.

With these considerations in view, it is an object of the present invention to increase the effectiveness of machines employed for this purpose by providing a machine which, in addition to pounding the lasting margin into intimate contact with the insole, will act to iron out any wrinkles or high spots in the shoe bottom without necessitating an additional operation on the shoe.

To this end, the invention provides a shoe bottom pounding and ironing machine comprising a cylindrical roll having a plurality of peripheral ironing ribs, and a plurality of rows of pounding elements positioned between the ribs. The invention further contemplates means for heating the ribs to cause them to shrink the leather as they rub against it.

By the use of such heating means, the efficiency of the ironing ribs is substantially increased. The hot irons tend to shrink the upper material where it overlies the insole, and thus to eliminate many of the wrinkles formed when the lasting margin of the upper is attached to the insole.

The invention will be better understood when considered in relation to the accompanying drawing, in which

Fig. 1 is a front elevation of the machine, a part of the roll being broken away to show the details of its construction;

Fig. 2 is a section of the machine along the line II—II of Fig. 1, showing the pounding elements operating upon a shoe; and

Fig. 3 is a view similar to Fig. 2, showing the ironing element operating on a shoe.

As illustrated in the drawing, the machine comprises a frame 10, in which is journaled a shaft 12. A roll 14, comprising a hub 16, a web 18 and a rim 20, is mounted on the shaft and held rigid therewith by a pin 22 passing through the hub 16 of the roll and the shaft.

As has been pointed out, it is desirable that the roll should act to perform two functions, first, to pound the lasting margin into firm contact with the insole and, second, to iron out any wrinkles or irregularities so that the shoe bottom will be smooth and flat. The pounding action is effected by a number of rows of beater elements 24, which, as illustrated, are in the form of rings, though they may equally well be made in other shapes. These beater elements are loosely carried in a number of circular passages 26 formed axially of the roll, and intersecting its periphery, so that they form slots, the side walls of which are undercut to prevent the rings from flying out when the roll is rotated. It will be noted that the passages are somewhat larger in diameter than the rings. When the roll is rotating, centrifugal force causes the rings to move outwardly in the passages, there being sufficient clearance laterally between the rings to prevent binding. Lateral movement is limited, however, by two annular plates 28 fastened to the ends of the roll by screws 30. This construction permits the rings to yield inwardly when a shoe is pressed against them, and thus the row of rings as a whole will conform to the curvature of the shoe bottom. The rows of rings are staggered by using thicker rings 32 at the end of every other row to eliminate any possibility that spaces between the rings might form ridges in the leather. By this means, any ridge formed by one row of beater rings is pounded out by the next row.

The formation of the passages 26 leaves on the periphery of the roll a number of upstanding ribs 34. The surfaces of these ribs are smooth, and the corners are rounded off so that as the roll rotates and the ironing ribs rub over the surface of the shoe, there will be no possibility of the ribs catching on the upper material and cutting or tearing it. The combined ac-

tion of the rings and the ribs effects an alternate beating and ironing action which produces an excellent surface to which the outsole may be attached.

5 The efficiency of the ironing ribs is greatly increased, however, by the use of heat. To this end there are provided two gas jets 36 which project into the opening in the side of the roll between the hub and the rim so that their flame 10 is directed against the web 18, which transmits the heat to the ribs 34. To bring gas to the jets there are provided two pipes 38, running from a source of supply (not shown). The pipes are held in brackets 40 by set screws 42, the brackets being fastened to the frame by screws 44. In 15 order to assist in supporting the shoe S, a work rest 46 is provided, the work rest being held in a lug 48 on the frame by a set-screw 50.

In using the machine to prepare the bottom 20 of a shoe for sole attaching the operator rests one side of the work on the support 46, presses the lasted margin M of the shoe bottom against the rotating roll and moves the shoe lengthwise to present successive portions of the lasted margin 25 to the roll. In this position the beater elements 24, which are held in their outmost position in the slots 26 by centrifugal force, strike against the lasted margin and pound it into firm contact with the insole. As the operator increases the pressure on the shoe against the roll, the beater elements are forced inwardly in 30 the slots against the action of centrifugal force far enough so that the heated ironing ribs can act upon the shoe bottom. The smooth heated 35 surfaces of the ribs iron out any wrinkles in the lasted margin of the upper and because of the heat tend to shrink the leather slightly and cause it to conform more closely to the shape of the bottom of the last. Thus by the combined use of beaters and heated irons, the shoe bottom is made smooth and flat, ready to receive the outsole.

Having thus described the invention, what I claim as new and desire to secure by Letters 45 Patent of the United States is:

1. A shoe bottom pounding tool comprising a cylindrical roll having a plurality of spaced peripheral ironing ribs extending axially of the roll, and a plurality of rows of pounding elements positioned about the circumference of the roll between the ribs.

50 2. A shoe bottom pounding tool comprising a cylindrical roll having a plurality of spaced pe-

ripheral ironing ribs the side walls of which are undercut to form between the ribs a plurality of partially enclosed passages extending axially of the roll, and a plurality of beater elements slightly smaller than the passage and loosely 5 carried therein.

3. A shoe bottom pounding tool comprising a cylindrical roll having a plurality of spaced peripheral ironing ribs the side walls of which are undercut to form a plurality of circular slots, 10 and a plurality of discoidal beater members having a diameter smaller than the slot and loosely carried therein.

4. A shoe bottom pounding tool comprising a cylindrical roll having a plurality of spaced peripheral ironing ribs the side walls of which are undercut to form a plurality of circular passages which extend longitudinally of the roll and intersect its periphery, a plurality of annular beater elements having a diameter smaller than 20 that of the circular passage and loosely carried in the passage, and means for preventing substantial lateral movement of the annular beater elements.

5. A machine for operating on shoes comprising a frame, a shaft rotatably mounted in said frame, a pounding and ironing roll mounted on said shaft and having a plurality of spaced peripheral ironing ribs the side walls of which are undercut to form partially enclosed slots extending longitudinally of the roll, and a plurality of beater elements slightly smaller than 25 the slot and loosely carried therein.

6. A machine for operating on shoes comprising a frame, a shaft rotatably mounted in said frame, a pounding and ironing roll mounted on said shaft and having a plurality of spaced peripheral ironing ribs the side walls of which are undercut to form a partially enclosed slot, a plurality of beater elements slightly smaller than 30 the slot and loosely carried therein, and means for heating the ironing ribs.

7. A machine for operating on shoes comprising a frame, a shaft rotatably mounted in said frame, a pounding and ironing roll mounted on said shaft and having a plurality of spaced peripheral ironing ribs the side walls of which are undercut to form a plurality of circular slots, a plurality of discoidal beater members having a diameter smaller than the slot and loosely 40 carried therein, and means for heating the ironing ribs.
